Fig. 1.

FIG. 2.

FIG. 3.

FIG. 4.

FIG. 5.

FIGURE 1 is a perspective view of an electric organ or similar article, embodying my new design, with the keyboard casing shown in a tilted position;

FIGURE 2 is a top plan view of the electric organ, with the keyboard casing shown in a horizontal position;

FIGURE 3 is a front elevational view thereof;

FIGURE 4 is a rear elevational view thereof; and

FIGURE 5 is an end elevational view thereof, showing the end not illustrated in FIGURE 1.

The dominant features of the design reside in the portions shown in solid lines. The end shown in FIGURE 5 is the mirror image of the end not shown therein.

I claim:

The ornamental design for an electric organ or similar article, substantially as shown and described.
